UNITED STATES PATENT OFFICE.

WILLIAM ROBINSON, OF BOSTON, MASSACHUSETTS.

PEDICYCLE.

SPECIFICATION forming part of Letters Patent No. 278,185, dated May 22, 1883.

Application filed November 16, 1882. (No model.)

To all whom it may concern:

Be it known that I, WILLIAM ROBINSON, of Boston, in the county of Suffolk and State of Massachusetts, have invented a new and Improved Pedicycle, of which the following is a specification.

This invention consists, essentially, of two wheels in the same plane supporting a platform or foot-support situated between said wheels, preferably on or below the level of their axes, said platform being provided with suitable means whereby the foot can rest securely thereon while the pedicycle is propelled, somewhat after the manner of a roller-skate.

15 In the accompanying drawings, in which similar letters of reference indicate like parts, Figure 1 is a side elevation of my pedicycle. Fig. 2 is an enlarged view of Fig. 1. Fig. 3 is a cross vertical section of the same.

20 A A' are respectively forward and rear wheels on the same plane, and B is, a platform or foot-support hung between and supported by said wheels. This platform B is preferably (although not necessarily) a skeleton frame, 25 provided usually on its upper surface with points b for preventing the foot from slipping. Straps or other suitable devices may be attached, if desired, for securely holding the foot in position on the platform. The surface 30 of this platform B is preferably either on the line of the axles, as shown in broken lines, Fig. 1, or below said line, as shown in full lines, Fig. 1, as in case it is placed above said line there is danger of some twisting of the ankle 35 in the endeavors to keep the pedicycle upright and level. In order that the vibration or jar may be absorbed to some extent, the ends of the platform B are formed into sliding frames B', containing and resting upon springs C, 40 whose seats are the boxes D, surrounding the axles a. To prevent slipping, rubber tires e may be applied to the wheels.

In Fig. 2 provision is made for steering by means of the radiation of the axles. This is 45 accomplished by constructing the frames B' with sides inclining from the perpendicular, substantially as shown. If the user desires to turn to the left, for example, he bears down the left side of the pedicycle by bearing his 50 foot in that direction. The effect is of course to press down the frames B' on that side, com-

pressing the springs C, thus drawing the ends of the axles a in said boxes nearer to each other, (the axle ends approaching nearer to the tops of the frames B', and hence nearer to each other.) This of course radiates the axles. 55 When the pressure is even and the wheels upright the wheels are in line and the axles parallel.

Having thus fully described my invention, 60 what I claim, and desire to secure by Letters Patent, is—

1. A pedicycle consisting, essentially, of two wheels in the same plane, and a platform or foot-support between and supported by said 65 wheels, substantially as set forth.

2. A pedicycle consisting, essentially, of two wheels in the same plane, and a platform or foot-support between and supported by said wheels, the upper surface of said platform 70 being on a line which is not above the level of the axles of said wheels, substantially as and for the purpose set forth.

3. In a pedicycle, the combination, with the wheels A A', of a platform or foot-support 75 hung between said wheels and provided with the points b, substantially as and for the purpose described.

4. In a pedicycle, the combination, with the wheels A A', of the skeleton platform or foot-support B, substantially as and for the purpose described. 80

5. In a pedicycle consisting, essentially, of two wheels in the same plane, and a platform or foot-support hung between said wheels, the 85 combination, with the axles a and boxes D, of the frame B', substantially as and for the purpose set forth.

6. In a pedicycle consisting, essentially, of two wheels in the same plane, and a platform or foot-support hung between said wheels, the combination, with the axles a and boxes D, of the frame B', having sides inclining from the perpendicular, substantially as and for the purpose set forth. 90

7. In a pedicycle, a foot-platform resting on one or more springs supported by the axles of the wheels, for the purpose set forth. 95

WILLIAM ROBINSON.
